UNITED STATES PATENT OFFICE.

JACK EVANS, OF BRAMAN, OKLAHOMA, ASSIGNOR OF ONE-HALF TO NATHAN L. JONES
AND B. I. LITOWICH, BOTH OF SALINA, KANSAS.

GATE.

Application filed August 13, 1927. Serial No. 212 799.

The present invention relates to gates but the principle may also apply to garage doors or the like.

The invention particularly relates to that

5 type of gate which is adapted to be operated at a distance by a person in a vehicle or on horse back, who desires to pass through the gate-way without getting out of the vehicle or dismounting from the horse.

10 Objects of the invention are strength of construction, simplicity and ease of operation.

In general the objects are to improve gates of this character, and such improvement will appear in the following specification and 15 claim, and I do not wish to be limited in the scope of my invention except as I shall be limited by the claim.

Referring to the drawings:

Figure 1 is a side elevation of my invention 20 showing the gate in closed position in full lines and in open position in dotted lines.

Figure 2 is a plan view thereof.

Figure 3 is an end view.

25 Figure 4 is a detail of the track in section on line 4-4 of Figure 1.

Figure 5 is a modified form of the operating device.

Referring to the drawings in detail, the reference numerals 10, 11 and 12 indicate respectively the posts for the gate which forms the subject matter of the present invention. The 30 post 10 I may designate as the latch post and is disposed to one side of the posts 11 which are arranged in spaced relation with respect to each other and may be designated as the pivot or central posts, while the post 12 is disposed to the opposite side of the central posts and may be called the guide post.

Pivoted between and adjacent the upper 40 ends of the posts 11 through the instrumentality of a bolt 14 is a tilting beam 13. A guide frame is provided for the tilting beam and includes standards 15 and 16 secured to and rising from the beam as best shown in 45 Figure 1 of the drawings. These standards have suitably secured thereto intermediate their ends a brace bar 17 which extends below the upper ends of the posts 11 and is arranged for movement between the same. The guide 50 frame and the beam 13 are braced by means of a metallic strip 18 secured by bolts to the upper ends of the standards 15 and 16 and to the beam by bolts 19 and 20. Secured to the underside of said beam by the bolts 19 and 20 55 as well as by bolts 21 is a track member 22

which is rectangular in cross section and provided with a central slot arranged longitudinally therein to provide a guideway as shown in detail in Figure 4 of the drawings.

The latch post 10 is provided near its upper 60 end with a vertically extending elongated slot 24 thru which the end of the tilting beam projects as shown at 13^a in Figure 1 of the drawings. The end 13^a also projects through an aperture 25 in a sliding block or slide 26 65 mounted in guide straps 27 and 28 secured to the latch post and for a purpose which will presently appear. The aperture 25 is somewhat larger in its dimension than the end of the beam in order to afford sufficient play for 70 the beam in its rocking movement on the pin 14. The lower end of the slide 26 is connected by means of links 29 and 30 and with lever arms 31 and 32 which are pivoted to 75 posts 33 and 34 spaced on either side of the latch post and being connected together by a cross member 37 and secured thereto as by bolts 35 and 36. Said cross member is also secured to the latch post by means of bolts 38 and 39.

Suspended from the track member 22 on the beam 13 is a gate structure 40 which is provided with rollers 41 and 42 secured to the end of straps 43 and 44 which are connected to the gate. The gate structure is of any 80 usual construction and preferably includes a number of parallel slats 45 connected by end members 46 and 47 and braced by intermediate members 48, 49 and 50. The end members 46 and 47 which may be in the nature of strap 90 iron having their upper ends extending above the upper slats 45 and secured to a cross member 51 which is disposed at a slight angle with respect to the upper bar as shown in Figure 1. This cross member 51 has the straps 95 43 and 44 secured thereto by rivets 52 and 53.

When pressure is brought to bear on either of the lever arms 31 or 32 the same is depressed and the member 26 is slid upwardly in the brackets 27 and 28 rocking the tilting 100 beam 13 to the dotted line position shown in Figure 1. The gate will then move by gravity along the track 23 to the dotted line position shown in Figure 1. The post 12 is provided at its upper end with a slot 54 which receives the opposite end of the beam 13. Adjacent the lower end of the post 12 I provide an abutment member 55, the lower end of which may be sunk in the ground and the upper end secured to this post, said member 105 110

being inclined in a position to form a stop against which the gate 40 may abut when it reaches its open position and will further help to give the gate a start when the beam 5 is tilted in gate closing position. The gate may be provided with a suitable latch 60 which connects with the cross pin 61 in the latch post. A latch is preferably of the type which will automatically connect with the pin 10 when the gate abuts against the latch post.

An alternative construction is shown in Figure 5 for opening the gate and consists of a sliding beam 26 as shown in Figure 1, to the opposite ends of which are connected 15 the ends of a cable 63 which may be secured to any suitable standard or post not shown in the drawings or may be run over a pulley at its opposite ends. The cable is connected with the ends of the member 26 by means of 20 eye-bolts 64 and 65 and passes over and under pulleys 66 and 67, respectively, then down under pulley 68 and over pulley 69. The first named pulleys 67 and 66 being secured by bolts 70 and 71 to the latch post and the pulleys 66 and 69 are mounted in a bracket 72 secured to the latch post as at 75.

It will be apparent from the above description that I have provided a very useful and very simple construction by which a gate 30 may be opened by one approaching the same and wishing to pass therethrough without dismounting from a vehicle or from a horse as the case may be. It may also be opened by a pedestrian very simply either by working 35 the levers or by opening the latch and pushing the gate back.

The construction as shown will add to the

features of convenience that of strength and durability. It is to be understood that this principle may be readily applied to doors 40 such as those used on warehouses, or on garages where such a construction may be desirable, and I do not wish to be limited in the specific form or the specific application of my invention. 45

Having described the invention, what I claim is:

In a gate, a gate structure, a pair of central posts arranged in spaced relation with respect to each other, a rockable beam pivoted between said posts, a guide frame for said beam and including standards secured to said beam and rising therefrom, a brace bar arranged between the posts below their upper ends and connected to the standards intermediate the ends thereof, bracing means secured to the standards and top of said beam respectively, a track-way secured to the underside of said beam, rollers having connection with said gate structure and mounted in the track-way for movement in a substantially horizontal plane, side posts having slots therein to accommodate the ends of said beam, a vertical slide slotted for receiving one end of said beam to operate the latter and being mounted for movement on one of said side posts, means connected to the vertical slide to move the same for tilting the beam and means connected to the other side post and being adapted to receive the gate structure 65 to hold the same at an inclination when open. 70

In testimony whereof I affix my signature.

JACK EVANS.
